SHAVING APPARATUS

Filed Aug. 23, 1929

By C. P. Goepel,
Attorney
Inventor
Johannes Hagen

UNITED STATES PATENT OFFICE

JOHANNES HAGEN, OF GELSENKIRCHEN-UECKENDORF, GERMANY

SHAVING APPARATUS

Application filed August 23, 1929, Serial No. 387,852, and in Germany November 14, 1928.

My invention relates to improvements in shaving apparatus, and more particularly in shaving apparatus of the type comprising a frame or casing equipped with one or more 5 longitudinal slots and a rotary drum, the said drum and one of the longitudinal walls of the slot providing the blades for cutting the hair. The object of the improvements is to provide an apparatus of this type in which the 10 hairs bent laterally by one blade of the drum are cut by the next blade of the drum, and with this object in view my invention consists in providing a drum in which the edges of the successive blades are inclined relatively to 15 the blade provided by the casing alternately in different directions. Thus, if a hair is bent laterally by an inclined blade it is safely caught and shorn by the next blade which is inclined in the opposite direction. Another 20 object of the improvements is to provide an apparatus in which two drums are contained in a single frame or casing, the said drums rotating in opposite directions. Therefore the apparatus can be used in the manner of a 25 razor by always moving the same in the same direction, for example downwardly across the skin. Further, an object of the improvements is to construct the casing, and more particularly the comb formed thereon so that 30 the hair to be shorn is first bent outwardly and away from the skin, so that it is readily engaged by the blades. With this object in view my invention consists in providing the comb with a plane bearing face ending at its 35 leading side in a shoulder disposed substantially perpendicularly to the said face, the notches of the comb being extended forwardly beyond the said shoulder. Thus the said perpendicular shoulder erects the hairs, which 40 therefore pass in erected position between the notches of the comb.

Other objects of the improvements will appear from the following description.

For the purpose of explaining the invention an example embodying the same has been shown in the accompanying drawings in which the same reference characters have been used in all the views to indicate corresponding parts. In said drawings,

Fig. 1 is a sectional elevation showing the apparatus,

Fig. 2 is an elevation looking from the left in Fig. 1,

Figs. 3 to 5 are sectional plan views taken 55 respectively on the lines 3—3, 4—4 and 5—5 of Fig. 1, and

Fig. 6 is a detail sectional view on an enlarged scale showing the cutting blades of 60 the casing and drum and the comb.

In the example shown in the figures the apparatus comprises a frame or casing *a* made integral with a hub or handle *u*, the said frame or casing being open at both sides. On the said open sides of the casing substantially semi-cylindrical caps *d* and *f* are 65 removably mounted, for example by means of hinges *w* and latches *x*. Within the casing two rotary cutters *b* and *c* in the form of drums and each comprising two curved 70 blades *k* are mounted in arms *o* guided in eyes *p* secured to or made integral with the casing or frame *a*. In the example shown in the figures the bearings for the said rotary cutters comprise removable bearing blocks *m* 75 secured to the arms *o* and embedded in recesses *n* of the caps *d*, *f*, the said recesses being provided with elastic cushions *n*¹ of felt or the like providing elastic abutments for the bearing blocks *m*. The arms *o* are engaged 80 by a conical pin *q* made integral with a screw *r* screwing in a hole of the wall of the casing *a*. Thus, by screwing the conical pin *q* more or less inwardly the arms *o* and the rollers *b*, *c* are pressed outwardly with the bearings *m* 85 into yielding engagement with the cushions *n*¹. In addition springs *s* are provided which tend to spread the arms *o* apart.

The caps *d* and *f* are formed with longitudinal slots *g* bounded at one side by straight 90 edges *h* and their opposite sides by combs *i*, the edges *h* providing the cutting edges of the casing cooperating with the blades *k* of the drums, and the combs *i* providing guides for the blades *k* moving towards the edges *h*. 95 The combs *i* are provided at their outer sides with large plane bearing faces *i*¹ ending at the leading side of the apparatus in shoulders *y* disposed substantially perpendicularly to the faces *i*¹. In the operation of the appa- 100

tus the combs are moved across the skin with the shoulders γ directed forwardly, so that the said shoulders erect the hairs which pass into the notches of the combs in erect position.

5 The cutting edges of the blades k are slightly inclined relatively to the cutting edges h at an angle α indicated in Fig. 2, and the successive edges of the blades k are inclined in 10 opposite directions, as is likewise indicated in Fig. 2. If therefore a hair is bent laterally by the edge of one of the blades k , so that it is not shorn, it is safely engaged by the edge of the next blade k .

15 To the axes of the cutters b and c gear wheels 3 and 4 are secured, and the gear wheel 4 is in direct engagement with a gear wheel 5 carried by a driving shaft t mounted in the hub or handle u , while the gear wheel 3 is connected with the gear wheel 5 through the intermediary of an idle wheel v . Thus the cutters b and c are rotated in opposite directions.

20 By removing the caps d and f the cutters b and c can be readily removed from the apparatus for cleaning the same, the arms o remaining in position in the eyes p .

The operation of the apparatus is as follows:

25 The cutters b and c are rapidly rotated from the shaft t , and the apparatus is passed with one of the faces i^1 across the skin. Thereby the shoulder γ erects the hairs which pass into the notches of the comb i and are engaged between the cutting edge h of the 30 casing and the edges of the blades k . The rotating blades k are guided on the inner curved faces of the fingers of the comb i , so that any injury to the skin is prevented. The exact position of the blades k relatively to the comb i and the edge h is obtained by forcing the pin q more or less inwardly and between the arms o .

35 By providing cutting edges at both sides of the apparatus the apparatus can be passed across the skin always in the same direction.

40 In the construction shown in the figures the cutting edges of the casing are made integral with the caps d , f , and the blades k are made integral with the bodies of the cutters b , c . 45 But I wish it to be understood that my invention is not limited to these features, and that in some cases exchangeable edges and cutters are provided. By the manner of mounting the cutters b and c on the arms o the cutters bear on the caps d and f with uniform pressure. In some cases I provide independent supporting means for the bearings.

50 While in describing the invention reference has been made to a particular example embodying the same I wish it to be understood that my invention is not limited to the construction shown in the drawings, and that 55 various changes may be made in the general arrangement of the apparatus and the con-

struction of its parts without departing from the invention.

I claim:

1. A shaving apparatus, comprising a frame formed with a slot bounded at one side by a cutting edge and at its opposite side by a comb, said comb being formed with a plane outer face and at the leading side of said face with a shoulder, and a rotary cutter mounted on said frame and provided with a cutting edge cooperating with the edge of said frame.

2. A shaving apparatus, comprising a frame formed with a slot bounded at one side by a cutting edge and at its opposite side by a comb, said comb being formed at the leading side of its outer face and at a part of the length of the fingers of the comb with a shoulder, and a rotary cutter mounted on said frame and provided with a cutting edge cooperating with the edge of said frame.

3. A shaving apparatus, comprising a frame provided at opposite sides with a cutting edge, a pair of rotary cutters mounted on said frame and each having a cutting edge in position for cooperation with one of the cutting edges of said frame, a pair of adjacent arms mounted on said frame and each supporting one of said rotary cutters at both ends, and means engaging said arms for spreading the same apart.

4. A shaving apparatus, comprising a frame having a slot bounded at one side by a cutting edge, a comb carried by the frame and disposed at the opposite side of said slot, said comb having a flat outer surface adapted to contact with the skin and a shoulder at the leading side of said outer face adapted to engage and raise the hairs when the apparatus is moved over the skin, and a rotary cutter mounted on said frame and provided with a cutting edge co-operating with the edge of said frame.

5. A shaving apparatus, comprising a frame having a slot bounded at one side by a cutting edge, a comb carried by the frame and disposed at the opposite side of said slot, said comb having a flat outer surface adapted to contact with the skin and a shoulder at the leading side of said outer face adapted to engage and raise the hairs when the apparatus is moved over the skin, and a rotary cutter mounted on said frame and provided with a cutting edge co-operating with the edge of said frame and with said comb.

6. A shaving apparatus, comprising an open frame, a cap hingedly mounted on the frame and extending across the open part of said frame and having an intermediate slot therein bounded by a cutting edge, and a rotary cutter mounted on said frame and having a cutting edge in position for cooperation with the cutting edge of said cap.

7. A shaving apparatus, comprising a frame provided at opposite sides with a cut-

ting edge, a pair of rotary cutters mounted on said frame and each having a cutting edge in position for cooperation with one of the cutting edges of said frame, a pair of adjacent arms mounted on said frame and each supporting one of said rotary cutters at both ends, and a wedge pin adjustably carried by the frame and adapted to be forced between the arms for spreading the same apart whereby each rotary cutter is moved toward its respective cutting edge of the frame.

In testimony whereof I hereunto affix my signature.

JOHANNES HAGEN.
